J. L. CABLE

FOLDING CAMP CHAIR

Filed Nov. 19, 1924

Patented Nov. 24, 1925.

1,563,073

UNITED STATES PATENT OFFICE.

JULIUS L. CABLE, OF BOSTON, MASSACHUSETTS, ASSIGNEE TO THE CABLE CORPORATION, OF BOSTON, MASSACHUSETTS, A CORPORATION OF MASSACHUSETTS.

FOLDING CAMP CHAIR.

Application filed November 19, 1924. Serial No. 750,765.

To all whom it may concern:

Be it known that I, JULIUS L. CABLE, a citizen of the United States, and resident of Boston, in the county of Suffolk and 5 State of Massachusetts, have invented an Improvement in Folding Camp Chairs, of which the following is a specification.

This invention relates to that class of folding camp chairs or stools in which the bottom is of canvas or similar flexible sheet material and, more particularly, to chairs of this type which are constructed from semi-tubular metal.

In the construction of chairs of this type 15 considerable difficulty has been encountered in providing suitable means for attaching the canvas to the metal cross bars of the chair, attachment by means of rivets being unsatisfactory and unreliable, and the object 20 of my invention is to provide a simple and effective means for connecting the canvas seat of a camp chair of the above type with the cross bars of the chair which will be as strong as the material of which the seat is 25 constructed, and which is so arranged that the actual expense of construction will be no more than that of previously employed methods.

I accomplish these objects in the manner 30 hereinafter described and as illustrated in the accompanying drawings in which:

Fig. 1 is a side elevation of a folding camp chair embodying my invention.

Fig. 2 is a similar view showing the chair 35 folded.

Fig. 3 is a detail sectional view of one of the cross bars and top portion of one of the legs.

Fig. 4 is a longitudinal sectional view at 40 line $x-x$ of Fig. 3.

Fig. 5 is a sectional view of one of the cross bars.

Fig. 6 is a side view of a cross bar, partly 45 in section.

Fig. 7 is a detail view of one end portion of a cross bar prior to assembling.

In the drawing a common type of folding camp chair is illustrated, which comprises two pairs of legs 1 and 2 formed of semi-tubular metal and pivotally connected in the 50 middle thereof, so that they may fold in the usual manner, as shown in Fig. 2.

According to my invention I provide a pair of cross bars 3 and 4 for connecting the 55 opposite legs at their upper ends and a

strip of canvas or similar material 5, which is connected thereto at its ends to form a seat, the width of the canvas and length of the cross-bars corresponding. The cross bars 3 and 4 each comprising a strip of 60 metal, which is bent double, along the middle longitudinal line thereof, into U-form, and the edge portions thereof from points at a distance from each end are bent inward, or towards each other at right angles, to form 65 retaining flanges or lips 6. The upper end portions of the legs are flattened to form ears 7, which are adapted to enter sockets 8 at each end of the cross bars, the length of 70 said sockets to the lips 6 and the width of 75 said ears corresponding.

In assembling the parts above described, the canvas seat is turned over and sewed to provide with a simple form of hem 9 at 80 each end and give the canvas treble thickness at these points. The distance between the edges of the flanges 6 is only sufficient to permit a single thickness of the canvas to extend therethrough and in assembling the 85 canvas and cross bars the hems are drawn into the bars at either end, until the sides of the strip are even with the ends of the bars, in which position the canvas will extend between the edges of the flanges, and its hems will be retained within the bars by 90 their engagement with the flanges as shown in Fig. 5. The canvas is then wound part way around each bar and the sockets at the 95 ends of the bars are then placed on the ears 7, as shown in Figs. 3, 4, and 6. Rivets 9 are then passed through the sides of the 100 bars, the intervening ears 7 and hemmed portions of the canvas, and then these parts are clamped closely together by the riveting process as shown in Fig. 3. As thus 105 arranged the canvas extends from each bar about its outer side and over its upper edge, completely covering the exposed portions of the bar. The half turn, which is thus taken about each bar by the canvas, 110 relieves the strain which would otherwise be placed on the hem, which is drawn into engagement with the lips 6, to a substantial extent. This strain is further relieved by having the end portions of the canvas firmly clamped between the sides of the cross bars and ears on the legs. The canvas as thus arranged, completely covers the sides and top of the bar and gives the chair a finished appearance, and the strain on the canvas 115

will be uniformly distributed throughout its entire width. The cross bars, canvas and legs will also be securely bound together, so that these parts will be rigidly held in the relative positions shown.

The chair may be provided with a back 10 which is pivotally connected to opposite legs.

I claim:

19. 1. A folding chair having a pair of semi-tubular metal cross bars, two pairs of pivotally connected crossed legs, each having an ear at its upper end extending between the corresponding end portions of the sides of said bars respectively, the portions of the sides of each bar between said legs being inturned to form retaining lips, a seat consisting of a textile strip having each end portion extending into one of said bars 20 between the lips thereof and between one of its sides and the ears of the corresponding pair of legs, said strip having thickened end portions for engaging the inner sides of said lips and means for securing the end portions of the sides of the bars and the intervening ears and strip portions together.
25. 2. A folding chair having a pair of semi-tubular metal cross bars, two pairs of pivotally connected crossed legs, each having an ear at its upper end extending between the corresponding end portions of the sides of said bars respectively, the portions of the sides of each bar between said legs being inturned to form retaining lips, a seat consisting of a textile strip having each end portion extending into one of said bars between the lips thereof and between one of its sides and the ears of the corresponding pair of legs, said strip having thickened end portions for engaging the inner sides of said lips and means for securing the end portions of the sides of the bars and the intervening ears and strip portions together.

3. A folding chair having a pair of semi-tubular metal cross bars, two pairs of pivotally connected crossed legs, each having an ear at its upper end extending between the corresponding end portions of the sides of said bars respectively, the portions of the sides of each bar between said legs being inturned to form retaining lips, a seat consisting of a textile strip having each end portion extending into one of said bars between the lips thereof and between one of its sides and the ears of the corresponding pair of legs, said strip having thickened end portions for engaging the inner sides of said lips and having its end portions adjacent its edges disposed between the opposite sides of the bars and the adjacent ears and extended over each bar to the opposite bar and means for clamping said ears and adjacent strip portions between the adjacent portions of said sides.

4. A folding chair having a pair of semi-tubular metal cross bars, two pairs of semi-tubular metal, pivotally connected, crossed legs, each having its upper end portion flattened to form an ear, each ear being disposed between the sides of one end portion of a bar with its end seated against the middle thereof at its inner side, and the edge portions of the sides of said bars between said ears being inturned to form retaining lips, a seat consisting of a textile strip having each end portion extended into one of said bars between the lips thereof and between one of its sides and the ears of the corresponding pair of legs, said strip having thickened end portions for engaging the inner sides of said lips and means for securing the end portions of the sides of the bars and the intervening ears and strip portions together.

In testimony whereof, I have signed my name to this specification.

JULIUS L. CABLE.
